United States Patent Office.

HENRY BENTER, OF PITTSBURG, PENNSYLVANIA.

Letters Patent No. 65,049, dated May 28, 1867.

IMPROVED WASHING-POWDER.

The Schedule referred to in these Letters Patent and making part of the same.

TO ALL WHOM IT MAY CONCERN:

Be it known that I, HENRY BENTER, of Pittsburgh, in the county of Allegheny, and State of Pennsylvania, have invented a new and useful Improvement in Washing-Powder; and I do hereby declare the following to be a full, clear, and exact description thereof.

My washing-powder is designed to facilitate the process and lessen the labor of washing and cleansing textile fabrics of every kind, particularly when made up into articles of clothing, or otherwise used for purposes of personal comfort, and also to lessen the expense of such process.

It consists of a mixture or compound of carbonate of soda, ultramarine, or their equivalents, and cuttle-fish bone. The ingredient first named I use commonly in the purest state in which it can be obtained; and, practically, I find the English or best American sal-soda to be preferable to the other carbonates for the purposes designed. The proportions in which I mix the articles named are substantially as follows: for eighteen pounds of sal-soda, or for such quality of a less pure carbonate of soda as will give an equivalent of strength, one and one-half ounce of cuttle-fish bone, and one-half ounce of ultramarine, more or less, varying the proportions somewhat at pleasure, according to the strength of the ingredients, or the character of the articles to be cleansed. For the ultramarine, indigo or other vegetable blue may sometimes be substituted, though with less satisfactory results. I also sometimes substitute for the ultramarine a residual product thereof, sometimes known as ultramarine suds, which consists of its less soluble ingredients, and is a resultant in certain processes of coloring in which ultramarine is used. Any mode of compounding by which a good mechanical mixture of these ingredients is secured may be adopted; but I have found it best, after thoroughly pulverizing the ultramarine and fish bone, to mix them well together, then let this compound lie for one or two hours, whereby a more intimate union is effected, and afterwards mix it well with the sal-soda, which is also in a pulverized state. The powder is then ready for use.

In using it, in every ten gallons of water, usually boiling, I dissolve about two ounces of the powder along with about four ounces of common hard soap, usually sliced. The liquid being kept at a boiling heat for a short time, I put in the garments or other articles to be cleansed, and boil briskly for fifteen or twenty minutes, more or less, moving them about occasionally, whereby most if not all the dirt is removed. If any remains, a little rubbing and rinsing effectually complete the cleansing process, after which the garments may be wrung out of water slightly blued, if found necessary. Flannels, however, and delicately colored silks or other articles, should not be boiled, but may be readily cleaned, as above described, without boiling.

The chemical action of caustic alkalies in washing and cleansing processes is too well known to require a lengthy description. The union of the sal-soda and fish bone produces an alkali which saponifies any oily matter which may exist in the fabrics to be cleansed, loosens the dirt contained therein, and absorbs all soluble impurities. But its action is less severe than that of the caustic alkalies generally employed for such purposes, so that little or no injury is caused to the fabrics. I prefer the ultramarine to indigo or other vegetable blue, both on account of the great superiority of its color, and also on account of its obdurate character, whereby it resists the action of the acids and alkalies which exist to a greater or less degree in the other ingredients named. Fabrics treated by the process described are, I claim, more thoroughly cleansed, and with less injury, and are left with a clearer, whiter color than by the processes now generally in use, and also at a less expense.

In addition to the purposes above stated, I apply my invention to cleansing purposes generally, house cleaning, shampooing, bathing, &c. For such uses I dissolve a tea-spoonful or less of the powder in a wash-bowl of warm water, with a little soap, and apply it in the usual manner.

What I claim as my invention, and desire to secure by Letters Patent, is—

A washing powder or compound, composed of sal-soda, or its chemical equivalent, cuttle-fish bone; and ultramarine, or other equivalent coloring matter, mixed in about the proportions above stated, and substantially in the manner and for the purposes hereinbefore set forth.

In testimony whereof I, the said HENRY BENTER, have hereunto set my hand in presence of—

HENRY BENTER.
